DESIGN FOR A LABORATORY SCALE

Carl Louis Otto, New York, N. Y., assignor to The
Torsion Balance Company, New York, N. Y., a
corporation of New York

Application September 21, 1948, Serial No. 148,675

Term of patent 14 years

(Cl. D52—10)

To all whom it may concern:

Be it known that I, Carl Louis Otto, a citizen of the United States of America, residing in the Borough of Manhattan, city, county, and State of New York, have invented a new, original, and ornamental Design for a Laboratory Scale, of which the following is a specification, reference being had to the accompanying drawings, forming part thereof, wherein:

Figure 1 is a top plan view of a laboratory scale embodying my new design.

Fig. 2 is a front elevation of the laboratory scale shown in Fig. 1.

Fig. 3 is a side elevation of the laboratory scale shown in Figs. 1 and 2.

I claim:

The ornamental design for a laboratory scale, as shown.

CARL LOUIS OTTO.
